(57) **CLAIM**

We claim the ornamental design for a pair of earphones, as shown and described.

DESCRIPTION

FIG. 1 is a perspective view of a right earphone of the pair of earphones in accordance with the present design, the right earphone is shown separately for purposes of illustration.

FIG. 2 is a front view of the right earphone shown in FIG. 1.

FIG. 3 is a rear view of the right earphone shown in FIG. 1.

FIG. 4 is a left view of the right earphone shown in FIG. 1.

FIG. 5 is a right view of the right earphone shown in FIG. 1.

FIG. 6 is a top view of the right earphone shown in FIG. 1.

FIG. 7 is a bottom view of the right earphone shown in FIG. 1.

FIG. 8 is a perspective view of a left earphone of the pair of earphones in accordance with the present design, the left earphone is shown separately for purposes of illustration.

FIG. 9 is a front view of the left earphone shown in FIG. 8.

FIG. 10 is a rear view of the left earphone shown in FIG. 8.

FIG. 11 is a left view of the left earphone shown in FIG. 8.

FIG. 12 is a right view of the left earphone shown in FIG. 8.

FIG. 13 is a top view of the left earphone shown in FIG. 8.

FIG. 14 is a bottom view of the left earphone shown in FIG. 8; and,

FIG. 15 is a perspective view of a pair of earphones with a cord and a control interface in accordance with the present design.
